Application January 8, 1938, Serial No. 183,932

7 Claims. (Cl. 206—46)

This invention relates to packages or containers for articles, and more particularly to packages for handset telephones.

An object of this invention is the provision of a simple and economical package for holding and shipping articles wherein they may be securely held and positioned relative to each other and the package in such a way that damage to and chafing tending to mar the surface finish of the articles are substantially eliminated.

In accordance with the above object, the present invention contemplates in one embodiment thereof as applied to the packaging of handset telephones comprising a receiver and transmitter unit and a stand, a container carrying an appropriately shaped insert or separator formed from corrugated fibre board. The stand rests on the bottom wall of the container, and spanning the stand is the separator, upon which is mounted the receiver and transmitter unit, the lower end edges of the separator resting on the bottom container wall and the under surface of its upper wall engaging spaced upper points of the stand. Formed on the separator at each of its four lower corners are integral extensions interposed between the adjacent inner surfaces of the container and the sides of the stand which serve to hold the stand away from the container side walls, thus preventing friction tending to mar the finish of the stand.

Other objects and advantages of this invention will more fully appear from the following detailed description, taken in connection with the accompanying drawing, in which

Fig. 1 is a sectional plan view of a package embodying the features of this invention for holding a handset telephone, indicated in broken outline;

Fig. 2 is a vertical sectional view taken on the line 2—2 of Fig. 1;

Fig. 3 is a vertical longitudinal sectional view on a reduced scale taken on the line 3—3 of Fig. 1, and

Fig. 4 is a plan view of a blank for the separator, the full lines representing the cut edges and the broken lines representing scored or creased lines at which the blank is to be folded.

Referring now to the drawing in detail, an embodiment of the invention is illustrated, in the form of a shipping package 10, for one type of handset telephone, shown in broken outlines comprising a receiver 11 and a transmitter 12 carried at opposite ends of a handle 13, the whole forming a unit which is connected to a stand 14 by conductor cords 17 (Fig. 1), the stand having

a rectangular shaped base 18. A suitably dimensioned container for enclosing the telephone is indicated at 19 constructed in any usual and well known manner from any convenient material, such as, for example, corrugated fibre board or like materials.

In Fig. 4 is shown a blank for an insert or separator 20 which may be sheared or punched, for example, from corrugated fibre board or like materials. The blank separator 20 is formed with 10 transverse creasing or folding lines 23, indicated by broken lines, the blank being folded upon these lines when it is inserted in the container 19 where-in it assumes the position clearly shown in Figs. 2 and 3 with its lower edges resting on the bottom 15 wall of the container at opposite ends thereof, its opposite longitudinal edges abutting the opposite side wall of the container with a slip fit.

The separator 20 (Fig. 4) is sheared during the blanking thereof, as indicated at 24 and formed 20 with longitudinal fold lines 25, which provide portions 26, which are struck down when the separator is inserted in the container leaving an elongated opening 27 for receiving and positioning a central portion of the handle 13 of the receiver 25 and transmitter unit, as shown particularly in Fig. 2. Also formed in the separator 20 during the blanking thereof is a finger hole 30 to facilitate the removal of the separator when unpacking the container, and at one end there is formed 30 a semi-circular slot 31 through which the conductor cords 17 interconnecting the telephone stand 14 and the receiver and transmitter unit extends when the handset telephone is packaged, as shown in Fig. 1. Integrally formed on opposite longitudinal edges of the separator 20, during the blanking thereof, at each of its four corners are flaps or extensions 32 arranged to be folded into alignment with the referred to edges and at right angles to the main portion of the 40 blank upon creasing or folding lines 33, indicated by broken lines in Fig. 4.

In packaging a handset telephone of the type described the telephone stand 14 is inserted in the container 19 with feet 34 thereof resting upon the 45 bottom wall of the container, the stand at one end thereof being slightly spaced from one container end wall and leaving a considerably greater space between the opposite end of the stand and the corresponding container end wall, as shown in Fig. 50 3. The width of the container is such that the opposite sides of the stand 14 when inserted therein are slightly spaced from the side walls thereof, as shown in Figs. 1 and 2. The blank separator 20 is then folded on the lines 23, 25 and 55

33, as previously described, and inserted in the container 19 to assume the position shown wherein, referring particularly to Fig. 3, it will be noted that an upper edge 37 of the stand 14 at the right end thereof abuts the inside surface of a right hand inclined wall portion of the separator and an opposite vertical end wall 40 of the stand abuts the inside surface of a left hand vertical wall portion of the separator.

10 As clearly shown in Figs. 1 and 2 the extensions 32 of the separator 20 in their folded positions engage the opposite side walls of the stand 14 at the ends thereof. This arrangement not only spaces the stand 14 from the end and side walls 15 of the container 19 whereby deleterious friction tending to mar the surface finish of the stand is prevented, but it will be noted effectively prevents the stand 14 from shifting longitudinally and transversely in the container particularly when 20 the handset telephone is completely packaged.

In order to further reduce friction between abutting surfaces of the separator 20, container 19 and handset telephone, which tends to produce fiber dust, the inner surfaces of the container 25 and the surfaces of the separator may be sprayed with wax, or some other suitable protective material. In some cases it may be found necessary to spray or coat with wax only those surfaces of the separator extensions 32 which 30 abut the opposite side walls of the stand.

The separator 20 is supported at its under side intermediate the opposite inclined wall portions thereof upon opposite pairs of spaced upper cradle portions 42 of the stand 14, the cradle portions serving to support and locate the telephone handle 13 upon the stand 14 when the telephone is in use. To complete the packaging of the telephone handset the receiver and transmitter unit is placed upon the separator 20, as 40 shown in the drawing, lying upon its side, a portion of the handle 13 between the receiver 11 and transmitter 12 resting in the elongated opening 27 and the receiver and transmitter engaging and resting on the opposite inclined wall portions 45 of the separator, the outermost points of the receiver and transmitter engaging the opposite end walls of the container 19. The conductor cords 17 which interconnect the stand 14 and the receiver and transmitter unit extend from below the separator 20 through the slot 31 thereof to the upper side thereof and are arranged in looped formation and placed at one side of the telephone handle 13 upon the separator, as 50 shown fragmentarily in Fig. 1. The usual cover flaps of the container 19 are now closed in and suitably sealed and the packaging of the telephone handset is completed.

With the container closed and sealed it will be noted that the under surface of the container 60 cover flaps engage the upper surface of the telephone handset handle 13 and since the handle at a point opposite thereto is lodged in the elongated opening 27 of the separator 20 and the receiver and transmitter engage opposite end walls 65 of the container the unit will be effectively prevented from shifting its position.

From the foregoing description it will be apparent that a simple and economical structure is provided for packaging articles and particularly handset telephones whereby during handling, shipment or storage, no harmful displacement of the telephone handset parts relative to each other and the package elements will occur 75 and thus damage and deleterious friction tend-

ing to mar the surface finish of the parts are reduced to a minimum.

Various additional modifications and applications of the invention will suggest themselves to those skilled in the art and such modifications and applications as fall within the spirit of the invention are intended to be covered by the appended claims.

What is claimed is:

1. A package for articles comprising a container having a cover and a bridge-like separator carried therein spanning and engaging an article and supporting upon its upper surface an article engaged by the cover, said separator having a portion at one end parallel to the inner end wall of the container and effective to hold an end of the spanned article therefrom, an opposite end of the separator being inclined with its lower edge terminating at the lower inner corner of the container and its inner inclined wall engaging an edge of the article, said separator being effective to hold the articles from moving relative to each other and the package elements. 10

2. A package for articles comprising a container having a cover and a bridge-like separator carried therein spanning and engaging an article and supporting upon its upper surface an article engaged by the cover, said separator having inclined portions at opposite ends terminating at the lower inner corners of the container 25 and effective to hold opposite ends of the spanned article from engaging the adjacent inner end walls of the container, said separator being effective to hold the articles from moving relative to each other and the package elements. 30

3. A package for articles comprising a container having a cover and a bridge-like separator carried therein spanning and engaging an article and supporting upon its upper surface an article engaged by the cover, said separator having a portion of one end interposed between and abutting at opposite sides an inner end container wall and an end of the spanned article to hold them apart and terminating at one lower inner corner of the container, an opposite end of the separator being inclined and terminating at the opposite lower inner corner of the container and its inner inclined wall engaging an edge of the article, said separator being effective to hold the articles from moving relative to each other and the package elements. 40

4. A package for articles comprising a container having a cover and a bridge-like separator carried therein spanning and engaging an article and supporting upon its upper surface an article engaged by the cover, said separator at opposite ends terminating at the lower inner corners of the container and effective to hold opposite ends of the spanned article from engaging the adjacent inner end walls of the container, and folded extensions on the separator at each end thereof effective to hold the sides of the article from the adjacent inner side walls of the container, said separator serving to hold the articles from moving relative to each other and the package elements. 55

5. A package for articles comprising a container having a cover and a bridge-like separator carried therein spanning and engaging an article and supporting upon its upper surface an article engaged by the cover, said separator at opposite ends terminating at the lower inner corners of the container and effective to hold opposite ends of the spanned article from engaging the adjacent inner end walls of the container, and folded 70

- extensions on the separator at each end thereof effective to hold the sides of the article from the adjacent inner side walls of the container, the surfaces of the extensions adjacent the sides of the article having a protective coating to reduce friction therebetween, said separator serving to hold the articles from moving relative to each other and the package elements.
6. A package for articles comprising a container having a cover and a bridge-like separator mounted therein spanning and engaging an article and supporting upon its upper surface an article engaged by the cover, said separator having a vertical portion at one end interposed between and abutting at opposite sides the inner end container wall and an end of the telephone stand to hold them apart, an opposite end of the separator being inclined with its lower edge terminating at the lower inner corner of the container and its inner inclined wall engaging an edge of the article, an upper wall of the separator having an opening for receiving a portion of the article supported thereon, said separator being effective to hold the articles from moving relative to each other and the package elements.
7. A package for hand set telephones comprising

ing a container having a cover and a bridge-like separator carried therein spanning and engaging a handset telephone stand and supporting upon its upper surface a receiver and transmitter handle unit engaged by the cover, said separator having a portion at one end interposed between and abutting at opposite sides the inner end container wall and an end of the telephone stand to hold them apart, an opposite end of the separator being inclined with its lower edge terminating at the lower inner corner of the container and its inner inclined wall engaging an edge of the telephone stand, and folded extensions on the separator at each end thereof effective to hold the sides of the stand from the adjacent inner side walls of the container, an upper horizontal wall of the separator having an opening for receiving a portion of the telephone handle unit supported thereon, said separator being effective to hold the telephone stand and handle unit from moving relative to each other and the package elements.
